FLEXIBLE TRIGGER THROTTLE

Clifford E. Fitch, Bryan, Ohio, assignor to The Aro Equipment Corporation, Bryan, Ohio, a corporation of Ohio

Application October 24, 1945, Serial No. 624,259

6 Claims. (Cl. 74—503)

1

This invention relates to a flexible trigger throttle for a power tool, including a portable motor which drives a device such as, for example, a drill or screw-driver.

Such tools are usually formed with a protruding portion or handle adapted to be grasped in the hand of the operator with a trigger and an air valve operated by the trigger in the handle. In operation, the device driven by the motor is applied to the work, being guided by the handle, and the trigger is pulled by the operator's one finger to start the motor, similarly to the trigger of a gun. However, it has been found that such a tool may buck or catch on the work, and when using only one finger on the trigger, the tool is liable to get away from the operator, with possible damage to the tool and the operator.

It is an object of this invention to provide a tool which is so formed that it is firmly grasped by the operator at the time the trigger is pulled, so that it is unlikely for the tool to twist or buck out of the operator's hand.

It is another object of the invention to provide a trigger which is contacted by the two long fingers of the hand, that is, the index and middle fingers, and furthermore to so form the rest of the handle that the shorter fingers naturally have a good grasp thereon.

It is a further object of the invention to provide a trigger of the type described wherein considerable pressure must be exerted by two fingers before the trigger is effective to open the air valve.

It is an object of another embodiment of the invention to require two-finger contact of a trigger of the type described wherein pressure of one of the two fingers is effective to open the air valve.

With these and other objects in view, my invention consists in the construction, arrangement and combination of the various parts of my trigger throttle whereby the objects contemplated are attained, as hereinafter more fully set forth, pointed out in the claims, and illustrated in the accompanying drawings, in which:

Fig. 1 is a partial sectional view of a tool illustrating one embodiment of the invention; and

Fig. 2 is a fragmentary sectional view of a portion of the tool showing a second embodiment of the invention.

Referring specifically to the drawing in Figure 1, numeral 10 designates a casing, preferably formed of a plastic material and enclosing a motor 9 preferably operated by compressed air. A working head is shown at 11, for holding a drill or screw-driver. Since the motor and head form no part of the present invention, a detailed description of these parts is unnecessary.

The casing 10 is provided with a handle 12 to be

grasped by the operator. As will be apparent, the handle permits the operator to solidly grip the tool and a broad flat trigger 13 is positioned near the forward top portion of the handle 12 so that the index and middle fingers of the operator will contact the trigger 13 when grasped. The trigger 13 is received in a socket 14 and two fairly strong springs 15 and 16 adjacent the outer edge of the trigger 13 urge the trigger outwardly. The trigger 13 is loosely pivoted by a pin 17 on a plunger or rod 18 which enters a recess 19 on the inner surface of the trigger and is spaced a considerable distance from the walls of the recess. The other end of the rod 18 is connected to a valve 21 for controlling a supply of compressed air which enters the tool through a passage 22 and is conveyed to the motor through passages 23 and 24.

When the operator grasps the tool and presses the trigger, he must use two fingers to apply pressure on both sides of the rod 18, as otherwise the trigger will rotate about pivot pin 17 until one or the other edge engages the wall of the socket 14. Obviously the air valve 21 will not open because no longitudinal movement is imparted to the rod 18. Therefore a firm grip by the entire hand on the handle 12 is insured to depress the trigger against the action of both the springs 15 and 16.

Referring now to Fig. 2 for a detailed description of the second embodiment of my invention, like numbers are applied to like parts in the first embodiment. In this embodiment, the trigger 13 is provided with two slots or passages 31 and 32 which extend completely through the trigger in a horizontal direction adjacent the springs 15 and 16. Through pins 33 and 34 extend through the passages 31 and 32 and are anchored in the side walls 35 of the socket 14. The through pins engage the walls of the passages 31 and 32 nearest the handle 12. In this embodiment, the index and middle fingers of the operator naturally grasp the trigger 13, but pressure applied by only one finger will operate the air valve 21 because the through pins prevent rotation of the trigger about the pivot pin 17 without depressing one side of the trigger and moving the rod 18. The passages 31 and 32 are sufficiently large that sufficient horizontal movement is afforded to depress the rod 18 and open the air valve 21.

It is obvious that other devices than an air valve and a compressed air-operated motor may be controlled by the improved trigger and handle arrangement. For example, an electrical contact and an electric motor might be substituted for the air valve and compressed air motor.

Some changes may be made in the construction and arrangement of the parts of my trigger

throttle without departing from the real spirit

and purpose of my invention, and it is my intention to cover by my claims any modified forms of structure or use of mechanical equivalents which may be reasonably included within their scope without sacrificing any of the advantages thereof.

I claim as my invention:

1. In juxtaposition to a handle to be grasped by the hand of an operator, a flexible trigger throttle for a power tool comprising a trigger, said trigger being of such size and being so positioned that the index and middle fingers of the operator naturally rest thereon when the tool is grasped, a device to be moved by the trigger, means for connecting the trigger to said device comprising a pivoted connection which permits rotary motion of the trigger with respect to the point of connection, and a plurality of spaced resilient means located between said handle and the trigger for urging the trigger and the connecting means against the force applied by the operator in using the tool.

2. In a juxtaposition to a handle to be grasped by the hand of an operator, a flexible trigger throttle for a power tool comprising a trigger, said trigger being of such size and being so positioned that the index and middle fingers of the operator naturally rest thereon when the tool is grasped, a device to be moved by the trigger, a plunger for connecting the central portion of the trigger to said device, a pivotal connection between the trigger and the plunger, stops in said handle for the edges of the trigger and separate resilient means located between said handle and the trigger and in spaced symmetrical relation to said pivoted connection for urging the trigger and the plunger against the force applied by the operator in using the tool, said stops being so positioned that if pressure is applied to overcome the force of one of said resilient means only, the trigger strikes one of the stops before it depresses said plunger.

3. In juxtaposition to a handle to be grasped by the hand of an operator, a flexible trigger throttle for a power tool comprising a trigger, said trigger being of such size and being so positioned that the index and middle fingers of the operator naturally rest thereon when the tool is grasped, a device to be operated by said trigger, a plunger for connecting the central portion of the trigger to said device, a pivotal connection between the trigger and the plunger, said handle having a socket for receiving the trigger and including stops for the edges of the trigger and separate resilient means located between said handle and the trigger and in spaced symmetrical relation to said pivoted connection for urging the trigger and the plunger against the force applied by the operator in using the tool, said stops being so positioned that if pressure is applied to overcome the force of one of said resilient means only, the trigger strikes one of the stops before it depresses said plunger.

4. In juxtaposition to a handle to be grasped by the hand of an operator, a flexible trigger throttle for a power tool comprising a trigger, said trigger being of such size and being so positioned that the index and middle fingers of the operator naturally rest thereon when the tool is grasped, a device to be operated by the trigger, a plunger for connecting the central portion of the trigger to said device, a pivotal connection between the trigger and the plunger, said handle having a socket for at least partially

receiving said trigger, separate resilient means located between said handle and the trigger and above and below said pivoted connection for urging the trigger and the plunger against the force applied by the operator in using the tool, a horizontal slot formed in the trigger adjacent each of the resilient means, a pin extending through each slot and anchored at both ends in the walls of said socket, said pins being normally held in engagement with one portion of the slots by the action of the resilient means, whereby if pressure is applied to overcome the force of one of said resilient means only, the trigger pivots about the pin adjacent the other resilient means and motion is transmitted to said plunger to operate said device.

5. In juxtaposition to a handle to be grasped by the hand of an operator, a flexible trigger throttle for a power tool comprising a trigger, said trigger being of such size and being so positioned that the index and middle fingers of the operator naturally rest thereon when the tool is grasped, a device to be operated by said trigger, a plunger for connecting the central portion of the trigger to said device, a pivotal connection between the trigger and the plunger, separate resilient means located between said handle and the trigger and above and below said pivotal connection for urging the trigger and the plunger against the force applied by the operator in using the tool, a horizontal slot formed in the trigger adjacent each of the resilient means, a pin extending through each slot and anchored at both ends in said handle, said pins being normally held in engagement with one portion of the slots by the action of the resilient means, whereby if pressure is applied to overcome the force of one of said resilient means only, the trigger pivots about the pin adjacent the other resilient means and motion is transmitted to said plunger to operate said device.

6. In juxtaposition to a handle to be grasped by the hand of an operator, a flexible trigger throttle for a power tool comprising a trigger, said trigger being of such size and being so positioned that the index and middle fingers of the operator naturally rest thereon when the tool is grasped, a device to be operated by said trigger, a rod disposed centrally of the trigger for connecting the trigger to said device, said rod being loosely pivoted to the trigger, and resilient means comprising two springs located between said handle and the trigger for urging the trigger and the connecting rod against the force applied by the operator in using the tool, said springs being so positioned that they are approximately under those portions of the trigger which are contacted by said index and middle fingers.
